UNITED STATES PATENT OFFICE.

MOSES H. WIENER, OF PHILADELPHIA, PENNSYLVANIA, ASSIGNOR OF ONE-HALF TO WILLIAM A. LAVERTY, OF SAME PLACE.

DESIGN FOR A SHOW-CARD.

SPECIFICATION forming part of Design No. 13,463, dated November 28, 1882.
Application filed October 16, 1882. Term of patent 7 years.

To all whom it may concern:

Be it known that I, MOSES H. WIENER, a citizen of the United States, residing in Philadelphia, Pennsylvania, have invented a Design for a Show-Card, of which the following is a specification.

My design, as shown in the accompanying drawing, comprises a representation of a shirt-collar, A, and the front of a vest, B, the card being intended for the display of a neckscarf

at the opening x.
The portion B of the card need not necessarily represent a vest, as it may be made to represent a coat, or coat and vest, the general

character and appearance of the card not being altered by such changes.

I claim—

The within-described design for a show-card, said design comprising the representation of a shirt-collar and a vest or like article of apparel, all substantially as described and shown.

In testimony whereof I have signed my name to this specification in the presence of two subscribing witnesses.

MOSES H. WIENER.
